UNITED STATES PATENT OFFICE.

ATMARAM A. BHISE, OF BOMBAY, INDIA.

NON-REFILLABLE BOTTLE.

SPECIFICATION forming part of Letters Patent No. 590,875, dated September 28, 1897.

Application filed July 23, 1896. Serial No. 600,224. (No model.)

To all whom it may concern:

Be it known that I, ATMARAM A. BHISE, of 5
Bombay, India, have invented a new and Improved
Non-Refillable Bottle, of which the
following is a full, clear, and exact description.

This invention relates to a class of bottles
used for trade purposes to hold in a sealed
condition liquid goods, such as alcohol or
10 malt liquors or proprietary medicines, and
has for its objects to provide a receptacle of
the indicated character which will be of novel,
simple, and practical construction, be adapt-
ed for convenient filling, be readily closed to
15 seal its contents by ordinary means, and be
capable of certainly and plainly exposing any
attempt to refill the bottle after its contents
have been unsealed and partially or entirely
decanted therefrom.

20 The invention consists in the novel con-
struction and combination of parts, as is
hereinafter described, and defined in the
claims.

Reference is to be had to the accompanying
25 drawings, forming a part of this specification,
in which similar characters of reference indicate
corresponding parts in all the figures.

Figure 1 is a side view of a bottle having
the improvements. Fig. 2 is a sectional side
30 view showing the interior construction of the
improved bottle, and Fig. 3 is a transverse
sectional view of the upper portion of the
bottle on the line 3 3 in Fig. 2.

The improved liquid-holding device may
35 be constructed of various shapes and dimen-
sions to suit the character of the liquid goods
it is to hold as a merchantable package.

In the drawings the features of the invention
are shown applied to a bottle for holding
40 whisky as an original package, and said bot-
tle may be protected by a trade-mark that
will be completely obliterated when the sealed
vessel is opened and liquor poured therefrom,
or there may be other means based on the
45 same principle employed in connection with
the novel mechanical construction of the bot-
tle to indicate the abstraction of contents of
the original package or the substitution of
inferior liquor for that first placed in the bot-
50 tle, as will now be specifically described.

The body 10 of the bottle is of the usual
form, and, if desired, may be of a capacity to

hold a quart of liquor, as is usual for such
liquor-bottles.

At a proper distance from the bottom of 55
the bottle, preferably commencing at the
point where the body is initially contracted
to produce the neck 10^a thereon, there is an
annular chamber 11, produced by the forma-
tion of an inner wall 12 on the body 10. 60

The wall 12, that is suitably spaced from
the outer wall of the bottle that forms the ex-
terior neck 10^a, is preferably made to sub-
stantially conform in shape with that of the
external wall, as is clearly shown in Fig. 2, 65
and said inner wall is integrally united with
the outer wall by fusion or other means.

The neck 12^a—that is, the upper portion of
the wall 12—is to be joined with the upper
edge of the outer wall 10^a after certain novel 70
detective features are introduced within the
annular chamber 11, and at a correct dis-
tance from the upper edge of the neck-wall
12^a a series of perforations *a*, of compara-
tively small diameter, are produced, thereby 75
affording a plurality of communicating pas-
sages between the pouring-neck of the bottle
and the annular chamber 11 near the top of
the latter.

One means for detecting the abstraction of 80
the liquid contents of the bottle that has been
filled—say with a superior brand of whisky—
consists in the provision of a trade-mark or
other printed or written matter, such as a
label or the like, contained on a strip of pa- 85
per or cardboard and placed in the annular
chamber 11, with its imprinted surface outer-
most, so that the printed or written matter
will be plainly visible through the outer wall
of the bottle. 90

The trade-mark or label 13 should be im-
printed or written with ink that is fugitive
and that will be washed out with alcoholic
liquor or, if there is no alcohol in the stored
contents of the bottle then the trade-mark or 95
label should be removable by exposure to wa-
ter or a liquid composition of which water is
a constituent element.

There are numerous organic substances,
mineral and vegetable, or compositions of 100
the same, that may be utilized to print the
fugitive trade-mark or label with—as, for in-
stance, printing-ink formed with starch as a
base and colored with saffron will afford a

yellow color that is fugitive in alcohol. Any common shoe-blacking will imprint black and be removable with water.

Again, other well-known substances and compositions of matter may be utilized to print the trade-mark or label in one distinctive color and by saturation with the contents of the bottle be changed to another strikingly different color.

10 It will be seen that if a trade-mark or label 13 is first placed in the chamber 11 and the top of the chamber then hermetically sealed by fusion or other means and the imprinted legend is produced in color that will change 15 or be obliterated by exposure to the action of alcoholic liquor the act of pouring the liquor out of the bottle after its cork has been removed will cause a certain proportion of the liquor to pass into the chamber 11 through 20 the perforations *a* and saturate the trade-mark, so as to alter its color or completely obliterate its imprint. The neck 11^a is of such a diameter as will adapt it to receive a cork 14 of the usual dimensions, and when introduced 25 it will be evident that said cork will effectually seal the small perforations *a*, so as to prevent entrance of the liquor within the chamber 11, while the cork remains firmly inserted within the neck. A lead or other 30 metal cap 15 may be placed over the top of the bottle-neck and a filling of wax 16 be introduced between the embedded end of the cork 14 and said cap, which renders the appearance of the sealed bottle neat and will 35 indicate that the bottle has been tampered with if the cap and wax are removed.

Another means for exposing the removal of contents originally packed in the bottle consists in the provision of a suitable number of 40 small capsules or balls of sugar or other material that are readily dissolved by water. These balls 17 are to be placed in the chamber 11 previous to the hermetic sealing of its upper end, and said balls have greater diameter 45 than the perforations *a*, so that others cannot be substituted therefor. The removal of the cork 14 and an attempt to pour liquor from the bottle will cause some of the liquor to pass into the chamber 11 and instantly 50 melt the capsules or balls 17, as the reversed position of the bottle will fill with liquor the space in the annular chamber above said balls, and this liquor will descend to melt them when the bottle is again reversed.

55 The trade-mark device and the dissolvable balls may be used separately or together as a means for disclosing the removal of the contents originally packed in the bottle or the substitution of a counterfeit liquor or medicinal preparation therefor, as the case may be.

Having thus described my invention, I claim as new and desire to secure by Letters Patent—

1. A bottle having its upper end formed 65 with an outer and an inner wall integrally united with each other and spaced apart forming an annular chamber, the upper portion

of said inner and outer walls constituting the neck of the bottle, the said inner wall near its upper end being perforated, whereby when 70 liquid is poured from the bottle a portion of the liquid will pass into the said annular chamber through the said perforations, the said annular chamber being adapted to contain a medium which by its changed condition when acted upon by liquid passing from the bottle into the said annular chamber will indicate abstraction of some of the liquid from the bottle, substantially as described.

2. A bottle having an annular chamber extending from the upper end a predetermined distance downward, the said chamber being adapted to receive a fugitive medium, the inner wall of the said chamber being perforated near the upper end, a cork or the like adapted 80 to fit in the neck of the bottle and to close said perforations when in position, the said perforations establishing communication between the interior of the bottle and the said chamber, whereby when the cork is removed 85 and the liquid is poured from said bottle, a portion of the liquid contents will pass through the perforations into the said annular chamber to act on the fugitive material contained therein, substantially as described. 90

3: The combination with a bottle having its upper or neck portion formed with a double wall constituting an annular chamber, the inner wall of said chamber being provided with a series of perforations adapted to establish communication between the interior of the bottle and the said chamber, and a cork or the like held in the neck of the bottle and adapted to close said perforations, of a written or imprinted medium in the said chamber 105 which will change color or be obliterated when acted on by the liquid contained in the bottle, a portion of the contents of the bottle passing into the said chamber through the perforations when the contents is poured 110 from the bottle, substantially as described.

4. The combination with a bottle having its upper or neck portion formed with a double wall constituting an annular chamber, the inner wall of said chamber being provided 115 with a series of perforations, and a cork or the like held in the neck of the bottle and adapted to close said perforations, the said perforations when the cork is removed establishing communication between the interior 120 of the bottle and the said chamber, whereby when the liquid contents of the bottle is decanted a portion of said contents will pass through said perforations into the said annular chamber, of a written or imprinted medium and a dissolvable medium placed in the said annular chamber, and respectively 125 changed in condition when saturated by the liquid passing from the bottle into the said chamber, substantially as described.
